UNITED STATES PATENT OFFICE.

EARL G. WATROUS, OF CHICAGO, ILLINOIS.

SLOW-CLOSING FAUCET.

1,327,000.

Specification of Letters Patent.

Patented Jan. 6, 1920.

Application filed April 5, 1915. Serial No. 19,155.

To all whom it may concern:

Be it known that I, EARL G. WATROUS, a citizen of the United States, residing at Chicago, in the county of Cook and State of Illinois, have invented certain new and useful Improvements in Slow-Closing Faucets, of which the following is a specification.

My invention relates to a lavatory fixture of the slow-closing type and the object there-
10 of is to provide a simple and efficient construction of slow-closing valve mechanism including a new construction of piston and piston ring used in such mechanism and adapted to overcome the objections and diffi-
15 culties encountered in use of slow-closing valve mechanisms, particularly in connection with hot water faucets.

In the drawings, Figure 1 is a section partly in elevation of a faucet embodying
20 my invention; Fig. 2 a section on the line 2—2 of Fig. 1; Fig. 3 a section taken on the line 3—3 of the upper portion of the piston structure and showing the top of the piston chamber in plan; Fig. 4 a side elevation of
25 the piston; Fig. 5 a plan view of the piston ring and Fig. 6 an edge view thereof.

Referring to the present embodiment of
1 my invention, the faucet comprises the body
having the usual spout or discharge 2 and
20 inlet connection 3. In the present instance
the body portion or casing is formed in sev-
eral sections including the top shell or cas-
ing 4 and an intermediate shell or casing 5,
which three parts are secured together in
35 any suitable manner. Within the casing
there is arranged the slow-closing valve
mechanism and the valve for governing the
passage of the water from the inlet 3 to the
discharge 2, the same comprising a casing 6
40 in which is formed a water inlet chamber 7,
an outlet chamber 8 and a piston chamber 9.
The chambers 7 and 8 are connected by an
inlet opening 10 which is governed by
means of a valve 11, the chamber 8 commu-
45 nicipating with the discharge 2 of the faucet.

The valve 11 is carried at the end of a
piston rod or stem 12 secured in a central
bore of a piston 13. This piston has con-
50 nected to its upper side, preferably in a
flexible manner, a plunger 14 extending
through a top cylinder head or cap 15 whose
extended tubular portion or boss 16 forms a
bearing therefor. The upper end of this
55 plunger is connected to the compressible cap
or button piece 17 between which and the
cylinder head is interposed a coiled spring

18 adapted to hold the plunger and conse-
quently the piston in its upward position.

The piston stem 12 is provided with
transverse ports 19 and a longitudinal pas-
60 sage 20 communicating with the central bore
of the piston and with the upper end of the
piston chamber through the annular space
around the lower end of the plunger 14.
The escape or leakage of the water from the
65 upper end of the piston chamber is through
a restricted port 21 in the cylinder cap or
head 15 and thence downwardly through the
passage 22 between the outer wall of the pis-
ton chamber and the inner wall of the cas-
70 ing to the discharge 2. The degree of re-
striction of the port 21 is determined by the
adjustable screw 23. A suitable check valve
such as the ball 24 is provided in the passage
through the center of the piston.

Referring to the specific construction of
the piston 13 and the packing ring thereof,
the piston is cut away on its upper side to
form two annular surfaces or shoulders of
different diameters. Upon the shoulder of
80 the larger diameter is arranged an ex-
pansion piston ring 25 which, as shown in Fig.
5, is a split ring of eccentric shape, that is to
say, one side of the ring is wider than the
other side, the split side being of the lesser
85 width. This ring is made of non-corrodible
material which is unaffected by hot water
and the material preferably employed is
hard rubber. This ring is expanded to fit
the inner walls of the piston chamber by
90 means of a split ring shaped wire 26 whose
adjacent ends 26^a are turned at right angles
into slots 25^a at the meeting ends of the pis-
ton ring. It will be understood that the
spring 26 is positioned inside of the piston
95 ring and around the central reduced portion
of the piston as clearly shown in Fig. 2. By
preference, the ring is provided on one side
with a pin 25^b whose lower end enters a
socket in the piston, as shown in Fig. 1,
100 with the result that any possibility of the
turning of the ring is avoided.

An annular plate or ring 27 fits upon the
top face of the piston ring and the same is
held thereagainst with yielding pressure
105 by means of a spring 28 interposed between
it and the under side of the removable cap
29 which is screwed upon the upper re-
duced portion of the piston. The top of
the piston is provided with a transverse slot
13^a in which fits the cross pin 30 passing
transversely through the lower end of the

plunger 14, such pin being held in its place by means of the cap 29 which is screwed onto the piston until it comes into contact with the top face thereof. Describing the 5 operation, the parts are in closed position in Fig. 1 and assuming that it is desired to admit water through the faucet the button 17 is depressed thereby forcing the plunger 14 and piston 13 downwardly and forcing 10 the valve 11 from its seat to open communication from the water inlet through the port 10, chamber 8 to the discharge 2. As the piston is depressed the water present in the 15 lower end of the piston chamber 9 is forced upwardly past the ball valve and through the piston to the upper end of the piston chamber. The water under pressure leaks past the piston stem 12 and into the lower end of the piston chamber, the pressure of 20 which water together with the tension of the spring 18 forces the piston upwardly at a slow rate of speed after the operator has released the button piece 17. The water in the chamber above the piston will then be 25 forced through the restricted port 21 where the rate of closing speed of the piston and the valve is determined. The valve will thereupon be seated to close the port 10 thereby closing off the supply of water 30 through the faucet.

By the use of my invention, I provide a simple and efficient form of slow-closing valve mechanism which has advantages particularly as to the piston construction because it is comparatively simple in 35 construction and provided with a piston ring which is unaffected by hot water and therefore always gives a proper working fit between the piston and the walls of the piston chamber for proper and efficient operation of the parts as required in a slow-closing 40 valve mechanism. In addition the construction described provides a flexible connection between the plunger 14 and the piston which is of advantage in assembling 45

the parts as it renders unnecessary absolutely accurate alinement between the different sections of the fixture.

I claim:

1. In a slow closing valve mechanism the 50 combination of a piston chamber, a piston therein having a check-valved passage through itself, a valve operated by the piston, said piston being cut away to form two annular portions of different diameters, 55 a piston ring on the portion of the larger diameter, a flat annular plate or washer resting on the portion of the lesser diameter and bearing on the piston ring to hold it in place on the piston, a plunger co-operating 60 with the piston, a cap secured to the piston and co-operating with the washer and with the plunger, and a spring between the cap and washer.

2. In a slow closing valve mechanism, the 65 combination of a piston chamber, a piston therein having a check-valved passage through itself, a valve operated by the piston, a cap having a central opening registering with said passage and secured to the 70 piston, a hand-operated plunger extending into said opening and passage, and a pin passing transversely through said plunger and confined below the cap.

3. In a slow closing valve mechanism, the 75 combination of a piston chamber, a piston therein having a check-valved passage through itself and a diametrical groove on its top surface, a valve operated by the piston, a cap having a central opening registering 80 with said passage and fitted onto the top of said piston, a hand-operated plunger whose lower end extends through said opening and into said passage, and a pin passing transversely through the lower end of the plunger 85 and received by said groove.

EARL G. WATROUS.
